CLAIM

The ornamental design for an irrigation solution bag, as shown and described.

DESCRIPTION

FIG. 1 is a perspective view of the irrigation solution bag embodying our design;

FIG. 2 is a front view thereof;

FIG. 3 is a right side view thereof;

FIG. 4 is a left side view thereof;

FIG. 5 is a bottom view thereof;

FIG. 6 is a top view thereof; and,

FIG. 7 is a back view thereof.

The broken line showing of parts of the drawings is included for the purpose of illustrating use and environment and forms no part of the claimed design.

1 Claim, 4 Drawing Sheets
